US00D857665S

(12) **United States Design Patent** (10) **Patent No.:** **US D857,665 S**
(45) **Date of Patent:** **** Aug. 27, 2019**

(54) **COMPUTER ACCESSORY DEVICE**

(71) Applicant: **Hewlett-Packard Development Company, L.P.**, Houston, TX (US)

(72) Inventors: **Eric Young**, Boise, ID (US); **Matthew B. Clark**, Vancouver, WA (US); **Cathy YaChuan Chen**, Boise, ID (US); **Pierre Harper**, Boise, ID (US); **Steven M. Frane**, Boise, ID (US); **Greg P. Pietz**, Boise, ID (US); **Samuel Yuichi Ogami**, Palo Alto, CA (US); **Nash Steven Stanton**, Boise, ID (US)

(73) Assignee: **Hewlett-Packard Development Company, L.P.**, Spring, TX (US)

(**) Term: **15 Years**

(21) Appl. No.: **29/646,142**

(22) Filed: **May 2, 2018**

(51) LOC (12) Cl. **14-03**

(52) U.S. Cl.

USPC **D14/218**

(58) **Field of Classification Search**

USPC D14/218; D13/168

CPC G09G 5/00; G06F 3/033

See application file for complete search history.

(57) **CLAIM**

The ornamental design for a computer accessory device, as shown and described.

DESCRIPTION

FIG. 1 is a top, front, left-side perspective view of a computer accessory device in accordance with our new design;

FIG. 2 is a front view thereof;

FIG. 3 is a rear view thereof;

FIG. 4 is a right-side elevation view thereof;

FIG. 5 is a left-side elevation view thereof;

FIG. 6 is a top plan view thereof; and,

FIG. 7 is a bottom plan view thereof.

The broken lines immediately adjacent the shaded area represent the bounds of the claimed design while all other broken lines are directed to environment and are for illustrative purpose only. The broken lines form no part of the claimed design.

1 Claim, 6 Drawing Sheets
